FRED K. LEWIS, OF ASHTABULA, OHIO

TOP FOR VEHICLES AND THE LIKE

Application filed November 3, 1922. Serial No. 598,784.

The present improvements relate more particularly to tops of the so-called "one-man" type, such as are now extensively used on automobiles, wherein the extreme forward or 5 outrigger bow is carried by means of swinging arms pivotally attached to the upper portion of the main bow, or equivalent support, so that such arms with such outrigger bow extend substantially horizontally in the open 10 position of the top and together constitute what may be termed an articulated auxiliary bow.

The object of the invention is the adaptation of such an articulated auxiliary bow for 15 use with a single rearwardly inclining main bow. In such case it is necessary to carry from such articulated auxiliary bow at least two supplemental bows, if the top is to be of any considerable longitudinal extent, i. e., 20 if it is for use on a so-called phaeton type of body in contradistinction to a roadster type. In conjunction with such supplemental bows I provide at the same time means for interconnecting the same with each other and with 25 the forward portion of the auxiliary bow or outrigger bow proper, so that said bows will move in unison when the top is folded or unfolded; also means for rigidly supporting the outrigger structure from the main bow in 30 the open position of the top.

To the accomplishment of the foregoing and related ends, the invention, then, consists of the means hereinafter fully described and particularly pointed out in the claim, the 35 annexed drawing and the following description setting forth in detail certain mechanism embodying the invention, such disclosed means constituting, however, but one of various mechanical forms in which the principle 40 of the invention may be used.

In said annexed drawing:—

Fig. 1 is a side elevational view of a top supporting structure embodying my present improvements, such top being shown as 45 mounted on an automobile body or tonneau of conventional form; Fig. 2 is a broken view of a detail of such top; and Fig. 3 is a view, similar to Fig. 1, but showing a modification in construction.

It is, of course, a matter of indifference

whether the top is used on automobile, motor-boat or otherwise, and, depending upon its longitudinal extent, a smaller or larger number of bows, in addition to the outrigger structure of present interest, may be utilized. It 55 will also be understood that the term "bow" is used herein inclusively to designate not merely the wooden bow proper, but also the metallic sockets carrying the same, these parts when regarded in side elevation constituting 60 the equivalent of the so-called "sticks", as they are called, in the old wood structure. It is accordingly a matter of convenience to refer to the parts in the singular, as though the structure all lay in a single vertical plane, 65 since the parts do actually lie in such a plane.

As previously indicated, the top covering 1 is designed to be entirely supported through an appropriate outrigger structure from a single main bow 2. The latter, which is of substantial construction in view of the weight it is thus designed to carry, is pivotally supported upon or attached to the body at the point 3 in the usual manner, so that it may be laid down and carried in a substantially horizontal plane when the top is not in use. Normally, in the extended or open condition of the top, said main bow 2 inclines rearwardly 75 at an angle of approximately forty-five degrees to the horizontal, being held from rising higher by the top covering or rather by special straps (not shown), or extensions of the longitudinal strainers, which, as is well known, are used to connect the bows together and provide supporting means for the top 80 covering intermediately between said bows. For the purpose in hand such straps or strainers may be regarded as a part of the covering material.

The outrigger structure comprises a main 85 articulated auxiliary bow, or, as it is sometimes called, outrigger bow 6, the latter term referring more particularly to the outer portion or bow 7 proper, which is secured to the main bow 2 by means of an arm 8 (one on each side of course) pivotally attached to said main bow and to the rear end of such outrigger bow, and so constituting the inner portion of said articulated auxiliary bow 6. The point of attachment of this arm to the 100

main bow is preferably in line with, or just above, the side edge of the cover, so as to be hidden by the latter, and the joint 9 between said arm and the outrigger bow is a rule or lock joint disposed so as to prevent further bending of the arm in question, when extended in horizontal fashion, as in open condition of the top illustrated in Fig. 1.

Pivottally attached to the arm 8 are two supplemental bows 10 and 11, whose points of pivotal attachment are so spaced, and whose angular positions in the open condition of the top are so adjusted, by means presently to be described, as to support the top covering 1 at suitably spaced intervals between main bow 2 and outrigger bow 7. The rearmost supplemental bow 11 is provided with an extension or short arm 12 that is connected, through the medium of a link 13, with the main bow 2 at a point somewhat below the point of attachment of the side arm 8 to said main bow. A stop 14 on swing arm 8, just forwardly of the point of pivotal attachment of said supplemental bow 11, engages with the latter in the extended or open position of the top, so as to prevent further bending of the joint between extension 12 and link 13 and thus constitute a rigid connection of the parts in question under the weight of the arms 8 and parts carried thereby. However, upon breaking the joint between said extension 12 and link 13, the arms 8 can be swung downwardly against the main bow 2 and said link and supplemental bow 11 will at the same time be brought into parallel relation with said main bow.

Operative connections are in turn provided between said supplemental bow 11 and the forward supplemental bow 10 as well as with the outrigger bow 7. In the constructional form illustrated in Figs. 1 and 2, such connections take the form of a long link 15, one end of which is pivotally attached to such first named supplemental bow 11 and the other to said outrigger bow at a point beyond the joint 9 between said bow and swing arm 8. The forward supplemental bow 10 is in turn connected with said long link through the medium of a separate short link 16 that lies alongside of said bow in the open or extended condition of the top, said short link being pivotally attached at one end to said bow and at the other end to the link 15. The result of the foregoing construction is that when joint 9 is broken, the joint between extension 12 and link 13 will be simultaneously broken, or vice versa, and the two supplemental bows will be folded up in unison as the outrigger bow is swung back into parallel relation with the main bow, the reverse operation occurring when the top is being unfolded or open. The position of the several bows and links that comprise the outrigger structure, when the latter is folded back

against the main bow, is indicated in diagrammatic outline in Fig. 1.

In the construction illustrated in Fig. 3, the first modification consists in the substitution of a stop 17 on the joint between extension 12 and link 13, in place of the stop 14 on the swing arm 8 wherewith supplemental bow 11 contacts in the open position of the top, as in the first described construction. It will be obvious that such stop 17 will constitute a lock joint that will function in exactly the same way as said previously described stop 14 and it will also be obvious that either form of stop may be employed interchangeably in the top construction illustrated in Fig. 1 or in the modified form thus illustrated in Fig. 3.

The further modification in such last named figure consists in the doing away of the short link 16 whereby the forward supplemental bow 10 is operatively connected with the long link 15 and in the provision of a link 18 that is pivotally attached at one end to said forward supplemental bow and at the other end to the outrigger bow at a point lying beyond the point of attachment of said long link 15 to said outrigger bow. The mode of operation in the case of this modified construction of top will be in effect the same as that in the first described construction, the position of the several bows and links, composing the outrigger structure when folded back against the main bow, being diagrammatically indicated in dotted outline as in the case of Fig. 1.

Other modes of applying the principle of my invention may be employed instead of the one explained, change being made as regards the mechanism herein disclosed, provided the means stated by the following claim or the equivalent of such stated means be employed.

I therefore particularly point out and distinctly claim as my invention:—

In a top for vehicles and the like, the combination of support means tending to underlie the center of gravity of the opened top, and means including a main bow inclining rearwardly from the vertical in the open position of said top, a two-part articulated auxiliary bow having its rear portion pivotally attached to said main bow and adapted to project substantially horizontally therefrom in the open position of the top; a supplemental bow pivotally attached to the rear portion of such auxiliary bow and having an extension, said supplemental bow inclining forwardly in such open top position; a link adapted to extend out of alignment with such extension and connect it to said main bow below the point of attachment of said auxiliary bow thereto; means adapted to prevent further bending of the joint between such extension and said link in the open position of the top; a second supplemental bow pivotally attached to the rear portion of said

auxiliary bow forwardly of said first-named supplemental bow and inclining in the same direction; a rigid link connecting said first supplemental bow with said auxiliary bow at a point forwardly of the joint therein; and a short link flexibly connecting said link with said second supplemental bow.

Signed by me, this 30th day of October, 1922.

FRED K. LEWIS.
